[57] ABSTRACT

Apparatus for contact duplicating information carried by a continuous moving master strip onto a continuous moving duplicate strip, exemplified by a diazo roll film duplicator. The duplicate strip is driven from a point downstream of its separation from the master strip and carries the master strip by electrostatic attraction. An expandable film carriage in the processing chamber can be adjusted so as to maintain uniform residence time in the processing chamber. An integral charge assembly is provided which is releasably secured to the apparatus housing to provide ready changing of charge rollers for different strip sizes. The charge assembly incorporates an aligned rotational electrical contact mechanism, chamfered guide roller flanges for easy loading, and an ejection lever. Electrostatic charge is applied by moving the strips between a pair of high voltage rollers, the opposite edges of at least one of the rollers being cut away to increase the air path length. One of the rollers has an outer compliant surface and is carried by a yoke biased toward the other roller under adjustable tension. Various embodiments are provided to accommodate varying strip widths including a rotary elongate lamp assembly, an expandable alignment guide, variable width buffers and a variable width continuous strip loop chamber.

APPARATUS FOR CONTINUOUS CONTACT DUPLICATION

This is a division of application Ser. No. 170,186, filed Aug. 9, 1971, now abandoned.

BACKGROUND AND SUMMARY OF THE INVENTION

This invention generally relates to contact duplication apparatus. The advent of information storage, particularly from computer output devices, on microfilm and microfiche has given rise to the need for rapidly and inexpensively producing duplicates of such microfilm information. The information may be stored on film strips varying in width from 8 mm for certain types of microfilm to 9.5 in. for microfiche. In typical prior art devices film strips are wound around idlers and around a portion of a drum to bring the emulsions in face to face contact. Such arrangements are not satisfactory because the films are exposed in a non-planar zone which causes optical distortion resulting in a loss of resolution of the duplicate. Moreover, problems of synchronization and registration arise because the duplicate and master films travel over different distances as a result of differences in their radial spacing from the center of the drum, causing slippage and misregistration problems. Film tension generated by such devices can cause the films to stretch, curl and break.

To overcome these difficulties, various devices have been provided in which the strips are moved through a planar exposure zone and are maintained in registry by the application of a vacuum between the strips for compressing the strips through atmospheric pressure, or by the application of high pressure air, thereby preventing relative longitudinal movement between the strips. One example of the vacuum type device is disclosed in U.S. Pat. No. 3,468,606. An example of a high pressure fluid type of device is disclosed in U.S. Pat. No. 3,161,120. Other patents of interest herein are U.S. Pat. Nos. 2,408,310, 2,569,793, 3,054,339, 3,057,275, 3,120,163, 3,148,600, 3,161,120, 3,168,022, 3,169,465, 3,308,731, 3,320,867, 3,437,336 and 3,468,606. While these systems function satisfactorily under normal conditions, they suffer the disadvantage of requiring complex fluid pressure systems including motors, pumps, regulators, pressure switches, solenoid valves, air tanks, filters, and the like. Not only do the fluid systems increase the complexity and therefore the initial cost of the apparatus, but reliability and maintenance are not always satisfactory. Moreover, there are as a practical matter limits to the pressure contact which can be obtained through the fluid pressurizing systems which may affect the compressive or adherence force providing the registration. Registration problems can become particularly acute where high reduction in image size, common to microfilm and microfiche, place great demands on optical resolution during printing. These problems of fine resolution are increased by the requirement of high processing speeds so as to keep pace with film produced by film computer output devices. A more recently suggested means for maintaining master and duplicate strips in registration during movement is by electrostatically charging the two strips so that they strongly attract one another and prevent movement therebetween. Such devices allow movement of the strips through a planar exposure zone and avoid the complexity of components required for fluid

pressure systems, implementing components in particular,

The present invention provides contact duplication apparatus utilizing electrostatic charge to attract and closely adhere master and duplicate strips and provides a variety of implementing components and systems resulting in a duplicator of exceptional reliability and economy in construction and use. In particular, various novel components and systems are provided for utilization of the apparatus with a variety of strip sizes. In operation, a duplicate strip is fed from a supply reel into contact with a master strip fed from a supply reel or from a continuous loop supply. The strips are electrostatically charged and then moved through an exposure station and thereafter separated, the master strip being returned to a take-up reel or to a loop chamber. The duplicate strip passes into an expandable carriage contained in a processing chamber and from there travels to a take-up reel. Pressure differential buffers are provided adjacent each supply and take-up station to apply small constant tension to the strips and to isolate the reel motors.

In a particular embodiment only one of the strips is driven, the other strip being carried through the exposure station by electrostatic attraction to the driven duplicate strip. Means are provided to coordinate the speed of travel of the strips with the expansion or contraction of the expansion carriage so as to maintain a uniform residence time in the processing chamber.

In a number of further embodiments, an integral charge assembly is provided which is releasably secured to the apparatus housing to provide ready changing of charge and alignment rollers for different strip sizes. The assembly incorporates a projecting alignment member to accurately seat the assembly, an aligned rotational electrical contact mechanism, chamfered guide roller flanges for easy loading, magnetic securement to the apparatus housing and an ejection lever. Electrostatic charges are applied by moving the strips between a pair of high voltage rollers, the opposite edges of at least one of the rollers being cut away to increase the length of the air path to the other roller. One of the rollers has an outer compliant surface carried by a yoke and is biased toward the other roller under adjustable tension.

Various other embodiments are provided to accommodate varying strip widths, including a rotary elongate lamp assembly to more rapidly process narrow widths, an expandable downstream alignment guide, variable width pressure differential buffers and a variable width continuous master loop chamber. Air turbulence is provided in the loop chamber, a portion of which is utilized as an air blast to bias the master strip loop into its buffers.

While the invention is exemplified by contact printing apparatus utilizing a master photographic film and light sensitive duplicate film, the principles and components are also applicable to magnetic tape contact duplication wherein electromagnetic radiation in the thermal range, rather than the visible light range, is utilized. For purposes of convenience and description, the term "master" is used to mean any information-bearing strip which is not substantially affected by the conditions of exposure and which can be utilized to impart such information to a duplicate strip. The term "duplicate" is used to mean an initially unprocessed strip of material which is sufficiently sensitive to the conditions of expo-

sure to be modified in accordance with the information on the master strip and can be, for example, diazo film, silver halide emulsion film, low Curie point magnetic tape, or the like. In the apparatus exemplified by the drawings and descriptive portion of the specification, the master strip is an image bearing, otherwise transparent dielectric film and the duplicate is a light-sensitive dielectric material of the diazo type. The term "master" is also used to refer to one or more pieces of material in contact with a single duplicate, for example, two master strips of 16 mm film in side by side contact with a duplicate strip of 35 mm film.

BRIEF DESCRIPTION OF THE DRAWINGS

FIG. 1 is a front elevation view of an exemplary embodiment of a contact duplicating apparatus constructed in accordance with the present invention and including a control circuit shown in schematic overlay;

FIG. 2 is a schematic perspective view of an expansion carriage utilized in the exemplary embodiment;

FIG. 3 is a front elevation view of an electrostatic charge assembly utilized herein;

FIG. 4 is a sectional view taken along the line 4—4 of FIG. 3, in the direction of the arrows;

FIG. 5 is a sectional view of a portion of a charge assembly illustrating a magnetic catch utilized herein;

FIG. 6 is a side elevation view taken of a pair of charge rollers utilized herein;

FIG. 7 is a schematic perspective view of a lamp assembly utilized herein;

FIG. 8 is a sectional view taken along the line 8—8 of FIG. 7, in the direction of the arrows;

FIG. 9 is a schematic perspective view of the lamp assembly of FIG. 7 in a different rotational disposition;

FIG. 10 is a schematic top view, in partial cross section, of an alignment guide utilized herein;

FIG. 11 is a schematic top view of a portion of the strip transport including the alignment guide of FIG. 10;

FIG. 12 is a schematic front elevation view, partly in section, of a pressure differential buffer utilized herein;

FIG. 13 is a sectional view taken along the line 13—13 of FIG. 12, in the direction of the arrows;

FIG. 14 is a schematic front elevation view of a loop chamber utilized herein; and

FIG. 15 is a sectional view taken along the line 15—15 of FIG. 14, in the direction of the arrows.

DETAILED DESCRIPTION

As required, details of illustrative embodiments of the invention are disclosed. However, as above-stated, it is to be understood that these embodiments merely exemplify the invention which may take forms different from the specific illustrative embodiments disclosed. Therefore, specific structural and functional details are not necessarily to be interpreted as limiting, but as a basis for the claims. In this regard, although the illustrative embodiments described herein comprises a diazo film duplicator, many of the components and principles are fully applicable to the processing of other strips such as silver halide emulsion films, low Curie point magnetic tape, and the like.

Referring now to FIG. 1, there is illustrated an exemplary embodiment of an apparatus for contact printing of a duplicate light sensitive continuous duplicate strip

10 from a transparent image-bearing continuous master strip 12. The apparatus includes a housing having a front panel 14 supporting components for transporting and exposing the master and duplicate strips 10 and 12.

5 In this illustration the master strip 12 is a continuous loop of film contained in a loop chamber 16, but shafts 18 and 20 are provided for supply and take-up reels, shown in shadow at 22 and 24. The loop chamber 16 includes a top wall 26 defining an exit 28 and entrance 10 30 adjacent drive reels 32 and 34 operatively connected to the reels 18 and 20 to rotate therewith so that either loop or reel to reel mode of operation can be utilized without modification to the transport mechanism. In either case, the master film 12 is led through a pressure differential buffer chamber 36 of the vacuum type, through an electrostatic charge assembly 38, an exposure zone 40, around a separation roller 42, through another buffer chamber 44, and then back into the loop chamber 16.

20 The duplicate strip 10 is led from a supply reel 46 through a vacuum buffer chamber 48 into contact with the master strip 12 at the electrostatic charge assembly 38, through the exposure zone 40 while in close contact with the master strip 12 and after separation therefrom 25 onto a strip drive 50, into a processing chamber 52, from there through a vacuum buffer chamber 54 and onto a take-up reel 56. Various of the components involved in the transporting exposure and processing will be described hereinafter in more detail.

30 Six separately controlled motors are associated with the apparatus to separately control the duplicate strip supply and take-up reels 46 and 56, the master strip supply and take-up reels 18 and 20, or associated loop drive shafts 32 and 34, and to top and bottom drives 50 and 51. Each drive 50 and 51 is formed of drive rollers and geared adjacent rollers defining S-lock drives. The take-up and supply reels and shafts are controlled by the length of strip forming loops in the respective vacuum buffer chambers 36, 44, 48 and 54 so as to supply

35 and take up the strips in accordance with the speed of travel of the strips through the apparatus. At each buffer chamber, vacuum applied at one end draws the strip past an array of apertures behind which are located a series of reed switches. The reed switches are programmed so that the adjacent reel is advanced or retarded to maintain a preselected length of strip within the buffer loop, all in accordance with techniques well known to the art. Other means for sensing the length of the loops to control the speed of the reels can be used

40 and a variety of electromechanical and electrooptical devices are known.

45 In an embodiment of this invention, the bottom drive 50 is a tachometer drive, connected to the speed control (hereinafter described) and constitutes the sole motive force for transporting the duplicate strip 10 and master strip 12 through the charge assembly 38 and exposure zone 40. Prior art devices have driven both duplicate and master strips while in contact by winding both strips around a drive roller which, as above pointed out, because of the difference in their radial spacing from the center of the roller, results in slippage and misregistration problems. The present construction avoids these problems by driving only the duplicate strip 10, the master strip 12 being carried by the duplicate strip 10 by electrostatic adherence.

55 50 The duplicate film in this illustration is of the diazo type requiring development with ammonia and such

processing occurs in the chamber 52. Referring to FIG. 2, there is illustrated an expandable carriage or load elevator 58. The carriage 58 includes a top array 60 of cantilever idler rollers spaced from a bottom array 62 of similar rollers. The top array 60 is carried by a frame member 64 which is connected on each side to rear channel slides 66 and 68. The bottom roller array 62 is supported on a frame member 70 formed with forward projecting end members 72 and 74 which are connected onto opposite front channel slides 76 and 78. Sprocket chains 80 and 82 supported by rollers 84 interconnect the top and bottom roller arrays to provide relative movement therebetween. The frame member 64 carries a dependent shaft 65 formed with a latch 67 at its lower end which is engageable with a solenoid-operated (not shown) locking member 69.

Initially, the latch 67 is secured by the locking member 69 so as to place the carriage 58 in a closed position with the top and bottom roller arrays 60 and 62 closely spaced, thereby minimizing the leader length required for threading the film, and this position is illustrated in solid lines in the drawing. After loading, the locking member 69 is tripped by its solenoid upon starting the apparatus. The rollers 60 and 62 are expanded to positions indicated by dashed lines 85 and 87 as determined by the differential in speed between the tachometer drive 50 and top drive 51. To establish this differential, the shaft 65 carries a magnet 71 at its lower end which magnetically actuates one or the other of a pair of spaced reed switches 73 which provide a signal to the top drive, as indicated by the dashed line 75, to retard or advance to maintain the magnet 71 between the switches 73. In use, the duplicate strip 10 is threaded through the roller arrays 60 and 62, as illustrated in FIG. 1 so that the bottom roller array 62 is supported via the duplicate strip 10 by the top roller array 60. The end members 72 and 74 connected to the bottom roller array are weighted to bias the carriage 58 to an open position. This bias is balanced by the tension resulting from the speed differential between the tachometer drive 50 and the top drive 51, placing the roller arrays 60 and 62 at the positions indicated by dashed lines 85 and 87, respectively.

In furtherance of this embodiment, and referring back to FIG. 1, a speed control module 86 is provided including a control panel 88 which is connected to the motors controlling the supply and take-up reels and shafts 18-32, 20-34, 46 and 56 and to the motors controlling the drives 50 and 51. The control panel 88 includes a variety of speed designations digitally variable from 15 feet per minute to 150 feet per minute. The speed control circuit is shown in schematic overlay at 90 and it is seen that when a new speed is selected the signal thereof is simultaneously transmitted to the motor for the tachometer drive 50 and to the motor for the drive 51 controlled by the reed switches 73. When a greater speed is desired, a signal thereof is transmitted, as indicated by the arrows 100 and 101 to the tachometer and top drives, the top drive being modulated by the reed switches 73 to maintain the speed differential between the drives 50 and 51 so as to maintain the roller arrays 60 and 62 at full expansion, indicated at 85 and 87.

In a diazo duplicator, excess ammonia over that required for development will not harm the film. However, in a duplicator requiring thermal processing, the residence time in the processor should be uniform. Ac-

cordingly, in an alternative embodiment, the carriage 58 is expanded in accordance with the speed of the strip to obtain such uniform residence. In this embodiment, the reed switches 73 are only a pair in a larger array of reed switches 103. When a change in speed is desired a signal is transmitted to the reed switch array 103, as indicated by the dashed line 105, in correspondence to the new speed selected. The switches are programmed to control the top drive 51 (via line 75) at a speed providing the proper differential to maintain a length of strip in the processor appropriate to the tachometer drive 50 speed. In place of reed switches, one can use a potentiometer driven by the shaft 65.

Referring now to FIGS. 3-6, components of the electrostatic charge assembly are illustrated. There is provided an integral alignment and charge assembly 38 in which alignment and charge rollers of a predetermined width are carried and which is designed for plug in operation so that when it is desired to utilize the apparatus for a different film size, one need merely remove the integral charge assembly 38 and replace it with another assembly incorporating guide and charge rollers of the desired width. In this regard, the rollers shown in FIGS. 4, 5 and 6 have different width sizes to illustrate the variability of roller sizes that can be accommodated.

With specific reference to FIGS. 3 and 4, the duplicate and master strips 10 and 12 are threaded between a pair of guide rollers 106 and 108 for lateral alignment of the strips and are then fed between a pair of charge rollers 110 and 112. The top charge roller 110 is formed with an outer compliant surface of conductive rubber for maintaining close contact between the rollers and the outer surfaces of the sandwiched duplicate and master strips 10 and 12 (see FIG. 6). The top roller 110 is carried in yoke fashion by a pair of resilient spring bars 114 and 116 on its opposite ends and each spring bar is secured to the underside of an adjustment bar 118. The adjustment bar 118 is formed rearwardly with a bearing 126 and with a notched cam surface 122 which engages a spring loaded lock bar 124. Rotation of the adjustment bar 118 in its bearing 126 moves the lock bar laterally and then back, as indicated by the arrow, to successively engage notches in the cam surface 122, locking the spring bars 114 and 116 in a desired position. By rotating the adjustment bar 118, counter-clockwise in its bearing 126, the top charge roller 110 can be lifted from the bottom charge roller to release the duplicate and master strips 10 and 12. This permits side loading of a pre-spliced closed master loop.

By rotating the adjustment bar 118 clockwise, increasing bias can be applied to the top roller 110 to increase the tension on the sandwiched duplicate and master strips 10 and 12. This feature, in conjunction with the utilization of a conductive rubber roller surface, or other compliant surface, allows very close contact between the confronting surface of the duplicate and master strips 10 and 12 during application of the charge potential. Importantly, the compliant surface permits the application of a positive bias by compensating for irregularities, such as the occurrence of labels on microfiche film. Furthermore by applying spring force at each end of the top roller, cantering of the bottom roller 112 can be accommodated. Without such accommodation, the bottom and top rollers 110 and 112 would have to be secured in perfect parallel alignment so as to assure proper contact between the duplicate and master strips 10 and 12.

The integral alignment and charge assembly 38 must be accurately secured to the housing in alignment with other guide components and with the duplication zone 40. Securement means must be accessible from the front of the housing so that the assembly can be rapidly replaced. Furthermore, provision must be made for voltage hookup to each charge assembly. Referring to FIG. 4, and back to FIG. 1, the housing panel 14 supports a narrower elongate panel 128 across its width and this, in turn, is utilized to support other components including the control panel 88. The panel 128 is formed with an opening 130 through which extend coupling components carried rearwardly of the charge assembly 38. Referring additionally to FIG. 6, the lower roller 112' is secured to an axle 132' for rotation therewith and which extends rearwardly of the charge assembly 38 as shown by the dashed lines 132 in FIG. 4. The axle is supported in a bearing housing 134 which in turn is supported within an aperture 136 defined in alignment therewith in the housing panel 14. The axle 132 terminates in a rounded tip 138 which bears against a resilient electrical contact member 140 carried rearwardly of the housing panel 14 adjacent the aperture 136. The contact member 140 serves as an electrical brush for the axle 132 transmitting high voltage thereto and is connected to an electrical supply. The top roller 110' is connected by its bearing to ground, as illustrated schematically in FIG. 6. The electrical supply is a DC voltage source in the range of 4000-8000 volts with a current of a few microamperes. The charge rollers therefore create a potential across the film strips so as to produce opposite electrostatic surface charges on the strips which will cause strong attraction and adherence therebetween.

Referring additionally to FIG. 5, the charge assembly 38 includes a base plate 142 carrying a disk shaped magnet 144 on its rear side positioned so as to contact a region of the housing panel 14, which is constructed of magnetically conductive material.

The outer edges of the charge assembly base plate 142 are keyed, as indicated at 145, to matingly engage the elongate panel 128 adjacent the opening 130 to facilitate alignment of the charge assembly 38.

Referring again specifically to FIG. 4, the adjustment bar 118 is arranged so that its rear edge 146 abuts the housing panel 14. A bore 148 is formed lengthwise through the adjustment bar 118 and fits over a projecting alignment sleeve 119 which is secured rearwardly through the housing panel 14 and which is formed with a closed end 121 in the panel 14. The projecting sleeve in conjunction with the aperture 136 serves to rigidly secure and support the assembly 38 in proper alignment. A push rod 150 is disposed through the bore 148 and sleeve 119 with its rear end 152 in contact with the sleeve end 121. The bore 148 opens forwardly into a wider diameter bore 153 to accommodate a push button 154 attached to the forward end of the push rod 150. A spring 156 is disposed around the push bar 150 in the wider bore 152 to return the push button 154 to an extended position. In operation, one grips the knurled adjustment bar knob 120 pushing the push button 154 with his thumb, which serves to overcome the force of the magnet 144, dislodging the charge assembly 138 from the housing panel 14.

Referring to FIGS. 3 and 5, the charge assembly alignment rollers 106 and 108, as illustrated by the wider roller 106' in FIG. 5, are each formed with an

inner flange 158 and an outer flange 160 for retaining the edges of the duplicate and master strips. The alignment rollers 106 and 108 are spaced closely adjacent each other and in order to facilitate side loading of the strips the outer flange 160 on each roller is chamfered at 162 to a reduced diameter outer surface. The chamfered alignment flanges operate in conjunction with the planar exposure station 40 and front loading carriage 58 (FIG. 1) to allow virtually straight through threading.

It has been found that when the contact rollers are equal in width to the width of the film strips passing therebetween a sparkover may result through an air path between the ends of the rollers. The resistance to sparkover or breakdown of the air path between the electrically conductive roller ends depends upon humidity and altitude conditions. Since the resistance to sparkover is a function not only of the dielectric constant of the path over which the potential is impressed, but is also a function of the distance between the electrically conductive surfaces, the resistance to sparkover may be increased by decreasing the effective spacing between the ends of the conductive rollers, thereby increasing the length of the air path. Referring to FIG. 6, the effective distance between the adjacent edges of the rollers is increased by cutting away opposite edge portions 166 and 168 from the conductive rubber roller 110' so that its resultant opposite edges 168 and 170 are spaced inwardly a distance sufficient to increase the length of the air path to the adjacent edges 172 and 174 of the lower roller 112', thereby preventing sparkover. Suppression of sparkover will preclude degradation of the strip edges and will additionally eliminate scintillation which could have an adverse effect upon a light sensitive duplicate strip.

Referring now to FIGS. 7-9, there is illustrated another embodiment of the invention. In the processing of relatively wide strips of light sensitive material, such as a strip of microfiche 176 (FIG. 7), a relatively wide light beam is required to properly expose the strip along its entire width. On the other hand, when it is desired to process relatively narrow widths of film, such as 35 mm microfilm 178 (FIG. 9), only a narrow beam of light is required. In accordance with another embodiment of the invention, the reflector is conformed to the film size so as to apply a beam width commensurate with the film size. In the embodiment illustrated in FIGS. 7-9, the same lamp assembly is utilized for exposing both wide strips and narrow strips, but is rotated 90° when used with narrow strips so that the reflector exposes a greater length of the narrow strip than would otherwise be exposed. Accordingly, a bonus in processing speed is obtained allowing narrower widths of light sensitive strip to be processed at a substantially faster rate than otherwise possible. Referring to FIGS. 7 and 8, a lamp assembly 180 is illustrated including a 2000 watt mercury arc lamp 182 and reflector 184 therefor enclosed by a housing 186 defining an exposure region 188, protected by a plate of glass. The exposure region 188 has a substantially greater length dimension than width dimension. In FIG. 7, the housing is secured with its width dimension along the line of travel of the strips, as indicated by the arrow 190. The housing 186 is supported by an upright member 192 rotatably journaled at its lower end in a swivel joint having 90° lock positions, indicated schematically at 194, or equivalent structure. In FIG. 9, the lamp housing 186 has been ro-

tated 90° so as to be secured with its length dimension along the line of travel of the strips 178, as indicated by the arrow 196, thereby exposing a greater length of the narrower strip 178. In place of a mercury arc lamp, one can utilize any lamp which is compatible with the type of film being used in the duplication operation. Furthermore, a plurality of lamps can be contained within the lamp housing. Other means for conforming the reflector can be utilized, such as by changing the shape of the reflector.

Referring now to FIG. 10 in conjunction with FIG. 1, there is illustrated an alignment guide 198 which is disposed downstream of the exposure station 40. The alignment guide 198 includes an upright idler roller 200 carried by a support shaft 202 extending crosswise of the duplicate and master strips, indicated by dashed lines at 204. The support shaft 202 extends through a sleeve 206 supported rearwardly of an opening 208 formed in the housing panel 14. The shaft 202 is formed with a series of notches 210 spaced in accordance with the standard strip widths from 16 mm to 105 mm. A spring loaded bullet catch 212 carried rearwardly of the housing panel 14 communicates through an opening 214 in the sleeve 206 with selected notches to secure the lateral alignment guide 198 in position. To change the strip width accommodated by the alignment guide 198, one merely has to pull out or push in the support shaft 202, as appropriate, as indicated by the arrow 216, until the proper notch 210 is secured by the bullet catch 212. The lateral alignment guide 198 aids in assuring proper registration for exposure. It serves in conjunction with the alignment and electrostatic charge assembly 38 to eliminate a carrier or transport device for the strips while in the exposure zone, minimizing problems of scratching or rubbing between strips and a carrier, and eliminating problems of reflection when the strips are transparent. An idler roller 215 (FIG. 1) spaced just downstream of the alignment guide 198 aids in this support.

Referring to FIG. 11, a further aspect of the alignment roller 198 is illustrated. The bottom charge roller 112 is formed with side flanges which must be set apart a distance sufficient to accommodate the maximum tolerance of the type of strips 10 and 12 utilized. As a result, lengths of film will be conveyed which are only loosely held by the flanges, as illustrated in FIG. 11 by the space. The alignment roller is therefore spaced from the panel so as to bias the strips 10 and 12 against the rear flange of the roller 12, as indicated by the arrow 219. The strip material is sufficiently elastic over the distance between the roller 112 and alignment guide 198 so that all strip tolerances can be accommodated.

Another embodiment of the invention is illustrated in FIGS. 12 and 13 where there is shown a contractible pressure differential buffer, which may be any of the buffers 36, 44, 48 or 54 illustrated in FIG. 1. The buffer includes a housing 216 open at one end and defining a strip entrance and exit region 218 thereat. The housing includes opposite side walls 220 and 221 in the width plane of an enclosed strip, e.g., a duplicate strip 10. The side walls 220 and 221 are somewhat wider than the widest strip to be processed. A rear wall 222 is secured between the side walls and airtight therewith, and is formed with a series of apertures 224 aligned with reed switches for controlling the speed of an associated reel, as hereinbefore described. One of the aper-

tures 226 communicates with a vacuum source, not shown, carried rearwardly of the housing panel 14. The buffer includes a front wall 228 which may be transparent and which is disposed between the side walls 220 and 221. The side walls 220 and 221 are lined with felt 230 and 232 or other soft material to prevent damage to the film and to serve as an air seal with the side edges of the front wall. The front wall is snugly fit against the lining 230 and 232 and can slide toward and away from the rear wall 222, as indicated by the arrow 224. The side walls 220 and 221 are formed along lines below the felt linings with keyways 236 and 238 and are each formed with a series of notches 240 and 242 within the keyways. A spring loaded latching member 244 is carried exteriorly of the front wall 228 for engagement in the keyways with the notches 240 and 242. Release bars 246 communicate with the spring catches and are formed to release the catches when pressed together.

In the configuration illustrated in FIGS. 12 and 13, the front wall is at its most extended position to accommodate the widest strip 10 and in such position is closely adjacent the forward edge of the strip 10 while the rear wall 222 is closely adjacent the rear edge of the strip 10. When it is desired to utilize a narrower strip, one need merely press the release bars 246 together and push the front wall 228 to the desired position, the spring latching member 244 engaging the appropriate notches 240 and 242, such modified configuration being shown by dashed lines at 248.

Referring to FIGS. 14 and 15 there is illustrated an expandable loop chamber 16 for containing varying widths of a master strip loop 12. The rear wall of the loop chamber is defined by a panel 250 carried by the contact duplicator housing. The loop chamber includes a pair of opposite side walls 252 and 254 in the width plane of the enclosed length of master strip 12 and having a width at least as wide as the widest strip width to be accommodated. As previously noted, the loop chamber includes a top wall 26 defining a strip exit 28 and entrance 30. The chamber includes a front wall 256 which may be transparent and which is carried by opposite pairs of drawer slides disposed in channels 258, shown by dashed lines in FIG. 14 and in shadow in FIG. 15, formed in adjacent housing walls 260 and 262. Suitable detents are provided as known in the drawer art to stop the front wall 256 at any of a number of selected positions corresponding to various strip widths. When adjusted for a particular strip width, the front wall 256 is closely adjacent the forward edge of the strip 12 therein while the rear wall 250 is closely adjacent the rear edge of the strip 12. The top edge of the front wall is spaced somewhat below the top wall 26 so that it can be moved therethereunder. The front wall carries a bottom wall 264 which can be extended below the bottom ledge 266 of the housing. A handle bar 268 is strung across the front wall. To accommodate a different width strip, one need merely push on the handle to move the front wall 256 closer to the rear wall 250, bringing the walls in close proximity to the new strip, and such a configuration is illustrated by dashed lines at 270.

In order to prevent the master strip 12 from rubbing against itself, thereby unnecessarily wearing, air is flowed through the loop chamber by introducing the air into the bottom of the chamber through the space 272 between the bottom housing ledge 266 and bottom

chamber wall 264, as indicated by the arrows 274 in FIG. 14, to form an air bearing for the strip 12. Air can also be introduced at spaced locations elsewhere in the chamber, such as indicated at 276 and 278 to coast with the upflowing air to add turbulence and maintain the master strip 12 in a suspended, open looped configuration. The flow of air is from the bottom to the top loop chamber and the air impinges against the bottom of the top wall 26, escaping generally through the space between the top wall 26 and top edge of the front wall 256.

Referring additionally to FIG. 1, a further embodiment is illustrated. The top wall 26 is formed with a pair of slots shown by dashed lines at 274 and 276, which are at opposite ends of the chamber and which lay immediately beneath the open ends of the buffer chamber 36 and 44, respectively. Air from the loop chamber escapes through the slots 274 and 276 and is directed as a blast against the master strip 12 to bias the master strip into the buffer chambers 36 and 44. While this bias is not needed during operation of the apparatus, at startup it aids in carrying the master strip 12 into the buffer chambers, avoiding handling of the master strip 12.

It will be seen that the various embodiments dis- 25

closed herein provide for efficient, rapid and reliable duplication from a master strip to a duplicate strip to effect an accurate transfer of information. Various modifications and variations of the present invention are possible in light of the above teachings.

We claim:

1. In apparatus for contact duplicating information carried by a continuously moving master strip onto a continuously moving light sensitive duplicate strip, comprising an exposure zone and means for moving said master and duplicate strips in close contact through said exposure zone, the provision of:

a lamp assembly in said exposure zone for exposing said master and duplicate strips, said lamp assembly comprising a lamp and reflector for said lamp, said reflector having a substantially greater length dimension than width dimension, and means for securing said reflector with its length dimension along the line of travel of said strips thereat, to define a beam of light of first width in said line of travel, and for rotating said reflector and securing said reflector with its width dimension along said line of travel to define a beam of light of second width in said line of travel.
